CLAIM

The ornamental design for a terminal display stand with articulatable joints, as shown and described.

DESCRIPTION

FIG. 1 is a front top perspective view of the terminal display stand with articulatable joints;

FIG. 2 is a front perspective view of the terminal display stand with articulatable joints absent the terminal environmental structure;

FIG. 3 is a rear top perspective view of the terminal display stand with articulatable joints;

FIG. 4 is a rear bottom perspective view of the terminal display stand with articulatable joints;

FIG. 5 is a front elevational view of the terminal display stand with articulatable joints;

FIG. 6 is a rear elevational view of the terminal display stand with articulatable joints;

FIG. 7 is a left side elevational view of the terminal display stand with articulatable joints;

FIG. 8 is a right side elevational view of the terminal display stand with articulatable joints;

FIG. 9 is a top plan view of the terminal display stand with articulatable joints; and,

FIG. 10 is a bottom plan view of the terminal display stand with articulatable joints.

The broken line showing is for illustrative purposes only, and forms no part of the claimed design.
